UNITED STATES PATENT OFFICE.

EVERETT WHEELER, OF LOS ANGELES, CALIFORNIA.

COMBINED MUFFLER AND CUT-OUT.

Application filed May 10, 1923. Serial No. 637,956.

This invention relates to mufflers for the exhaust pipes of internal combustion engines, and has for its object to provide a combined muffler and cut-out.

5 An object of the invention is to provide a combined muffler and cut-out of extremely simple and substantially construction and which is of inexpensive and practical construction and is adapted to be readily inserted in the exhaust line of an automobile 10 motor.

Other objects and advantages will be made manifest in the following specification of an embodiment of the invention illustrated in 15 the accompanying drawings, wherein

Figure 1 is a side elevation of the motor as installed.

Fig. 2 is a longitudinal, sectional view of the muffler and cut-out.

20 Fig. 3 is an end view of the cut-out.

Fig. 4 is a cross section and end view on line 4—4 of Figure 2.

The present invention consists of a main exhaust line or pipe 2, having adjacent its 25 outlet end a cut-out valve 3, which is connected to an operating lever 4, to which is attached a spring 5 for normally throwing the valve 3 to a substantially closed position. The lever 4 is adapted to be operated by any 30 suitable means, as a foot pedal 6 mounted at the driver's station in the vehicle, and being connected by a link 7 to the lever 4, so that by a pressure on the pedal, the valve 3 may be opened to permit direct flow of exhaust 35 gases under considerable pressure through the muffler and cut-out.

The pipe 2 constitutes the central element of a muffler including a number of concentric tubes or shells 10, into the innermost of 40 which gases in the center pipe 2 will pass through an aperture 11 when the cut-out valve 3 is closed. The gases entering the inner tube around the main exhaust pipe 2 are caused to flow forwardly to the opposite 45 end of the muffler structure, and thence through an outlet 12 into the next expansion chamber, and so on, eventually discharging through apertures 13, which may be provided in one or the other of the heads 14 en- 50 closing the ends of the muffler tubes, and through which heads the cut-out or exhaust pipe 2 extends; the forward end of the cut-out pipe being connected to the usual exhaust pipe E, Figure 1.

55 A feature of the invention resides in the fact that the main exhaust pipe 2 is consid-

erably greater in diameter than the exhaust pipe of the vehicle E. It is well known that if the exhaust gases from an internal combustion engine are discharged from a small 60 exhaust pipe into a large exhaust pipe, a pleasing rumble or low roar is produced, when the cut-out is open, as distinguished from the sharp crack produced upon discharging the gases directly from the exhaust pipe of the vehicle into the open air. 65

Preferably, one of the heads 14 is detachably mounted on the cut-out pipe 2, so that it may be readily withdrawn over the end of the pipe to facilitate the separation and 70 cleaning of the tubes forming the muffler. The removable head 14 is shown as provided with a split hub 15, having ears through which passes a clamp bolt 16 by which the split hub may be contracted tightly to hold 75 the parts in the assembled position.

The device may be mounted in any suitable manner, and is shown as having a bracket 18, which may be clamped to the chassis frame F, or otherwise supported. 80

The heads 14 are shown as detachably secured on the interposed muffler shells as by means of tie bolts 19, passing longitudinally from end to end and through the heads.

Further embodiments, modifications and 85 variations may be resorted to within the principle of the invention.

What is claimed is:

1. A combined muffler and cut out comprising a main exhaust pipe adapted to be 90 connected to the exhaust pipe from the motor of a vehicle, said main exhaust pipe being materially greater in diameter than the diameter of the vehicle exhaust pipe, a valve mounted in the rearward end of the main exhaust pipe, a first head mounted about said main exhaust pipe forwardly of said valve, a second head mounted about said main exhaust pipe forwardly of the first head, said second head being positioned approximately at the middle of said main exhaust pipe, means providing two concentric annular shoulders upon the opposed faces of said heads, a first shell mounted between the heads against the inner shoulder, a second shell mounted between the heads about the first shell and disposed against the outer shoulder, there being a single aperture in the main exhaust pipe forwardly of the first head, a single aperture in the first shell behind the second head and another aperture 100 in the first head between the first and second 105 shells.

shells, and means for opening and closing said valve.

2. A combined muffler and cut out comprising a main exhaust pipe adapted to be connected to the exhaust pipe from the motor of a vehicle, said main exhaust pipe being materially greater in diameter than the diameter of the vehicle exhaust pipe, a valve mounted in the rearward end of the main exhaust pipe, a first head mounted about said main exhaust pipe forwardly of said valve, a second head mounted about said main exhaust pipe forwardly of the first head, said second head being positioned approximately at the middle of said main exhaust pipe, means providing two concentric annular shoulders upon the opposed faces of said heads, a first shell mounted between the heads against the inner shoulder, a second shell mounted between the heads about the first shell and disposed against the outer shoulder, there being a single aperture in the main exhaust pipe forwardly of the first head, a single aperture in the first shell behind the second head and another aperture in the first head between the first and second shells, said valve being in the form of a butterfly valve, a lever rigidly secured intermediate its ends to the butterfly valve, and a coil spring secured to one end of the lever and to the second shell normally holding the valve in closed position, the other end of the lever being adapted to be connected to a suitable actuating device upon the vehicle, whereby the valve may be opened against the action of said spring by said actuating device.

In testimony whereof I have signed my name to this specification.

EVERETT WHEELER.
